UNITED STATES PATENT OFFICE

2,460,380

GUN MOUNT

David Edgar, Lynn, Mass., assignor to United
Shoe Machinery Corporation, Flemington,
N. J., a corporation of New Jersey

Application October 30, 1945, Serial No. 625,528

2 Claims. (Cl. 89—37)

1

My invention relates to means by which a gun may be adjustably mounted upon a support, such as a turret.

It is an object of my invention to improve the mounting means of the gun so that but relatively little space will be required on the gun support for the members comprising the mounting means and the need for exact relationship between the members for their proper functioning will be eliminated, thus simplifying the construction of the members. This object is attained by pivoting a block on the gun and pivotally joining a link to the block, which link has rotatable thereon about an axis perpendicular to the axes of the pivots between the block and the gun a member rotatably mounted also on the support for pivotal movement about an axis parallel to said axes, means being provided for moving said member longitudinally of its connections with the support to adjust the position of the gun.

In the accompanying drawing illustrating a particular embodiment of my invention,

Fig. 1 shows, in side elevation, two guns, each of which is carried by my improved mount;

Fig. 2 is an enlarged view, partially in side elevation and partially in vertical section, of the mounting at the rear of one of the guns; and

Fig. 3 is a section on the line III—III of Fig. 2.

Considering one of the two guns G, the mounting being the same for both, it is carried upon the horizontal walls 61 of a housing 71 attached to the vertical wall 60 of a turret. The gun must not only be held in a normally fixed position upon the walls 61, but must also be capable of being bore-sighted, or arranged in the correct horizontal and vertical angles to correspond to an un-illustrated sight upon the turret. It is carried in a cradle 276, which may be considered as a part of the gun. To the under side of the forward extremity of the cradle the yoked head 277 of a spindle 278 is pivoted. The spindle passes loosely through a sleeve 279 threaded into a vertical opening in the housing-wall 61. On the sleeve is a lock-nut 280 for engagement with the housing-wall. When the sleeve is rotated, by an enlargement 281 upon its upper end on which the head of the spindle rests, it will either raise the forward end of the cradle or allow it to descend, the muzzle of the gun moving similarly in elevation.

To the cradle near the rear is connected means for permitting the vertical movement just described, and also for adjusting the gun-muzzle horizontally in azimuth. Pivoted at 282 about an axis extending laterally of the gun between lugs 284 depending from the cradle, is a block 286

2

having opposite trunnions 288, 288, the common axis of which lies longitudinally of the gun. On these trunnions hang a pair of plates 290, 290, at the inner sides of which are opposite shoulders 292 and which are secured to each other by bolts 294, 294. The two plates, thus attached, form a unitary link, which may be divided for assembling the mount. The shoulders support a headed shank 296 passing through an opening between the plates and having, below these, a horizontal lateral extension 298. The extension is provided at its outer ends with aligned, conical recesses 300, 300, the axis of which may lie parallel to that of the pivots 282. The shank furnishes one portion of a pivot for the extension at right angles to the pivots at 282. Into the recesses fit the ends of screws 302, 302 threaded through lugs 304, 304 upon the housing-wall 61.

Opposite rotation of the screws swings the muzzle of the gun horizontally, the pivotal rotation of the spindle 278 in the sleeve 279 and of the shank 296 and its extension upon the plate-shoulders 292 permitting this. The pivoting of the shank accommodates the rectilinear movement of the screws 302 to the arcuate movement of the pivots 282 about the axis of the spindle 278. When the muzzle is moved vertically by adjustment of the sleeve 279, the rear of the cradle swings correspondingly by virtue of the pivoting of the cradle-lugs 284 at 282 and of the extension 298 upon the screws 302. The freedom of the link-plates 290, 290, with the block 286, to move about their upper and lower lateral pivotal connections provides for the travel of the pivots 282 along a curved path while the sleeve 279 is rising vertically. It further prevents cramping during this vertical adjustment, if the axes of the pivotal connections at 282 and 302 do not lie in parallel planes. This may be due to poor machining or deformation in use.

It will be seen that all the mounting elements are readily manufactured with sufficient accuracy and easily assembled; that both longitudinally and laterally of the gun they occupy little space; and that their character and arrangement is such that they will remain effective under much of the rough usage to which a gun naturally is subjected.

Having thus described my invention, what I claim as new and desire to secure by Letters Patent of the United States is:

1. In a gun mounting means for connecting a gun to a support, a block rotatable about pivots on the gun, a link pivoted on the block, a member rotatable upon the link about an axis at right angles to said block pivots and pivoted to the sup-

port about an axis parallel to said block pivots, and means for moving said member longitudinally of its pivotal connection to the support to adjust the position of the gun.

2. In a gun mounting means for connecting a gun to a support, a block rotatable about pivots on the gun, plates pivoted at opposite sides of the block and provided with opposite shoulders, means for securing the plates to each other, a shank having at its upper end a head resting upon the shoulders of the plates and at its lower end a lateral extension, and screws threaded in the support and engaging in recesses in opposite sides of the extension, whereby rotation of the screws moves the gun longitudinally of the screws.
